(57) **CLAIM**

The ornamental design for a deployment tool for an encapsulation device, as shown and described.

DESCRIPTION

FIG. 1 is a perspective view of a deployment tool for an encapsulation device showing our new design;

FIG. 2 is a top view of the deployment tool shown in FIG. 1; FIG. 3 is a bottom view of the deployment tool shown in FIG. 1;

FIG. 4 is a back view of the deployment tool shown in FIG. 1; FIG. 5 is a front view of the deployment tool shown in FIG. 1; FIG. 6 is a left view of the deployment tool shown in FIG. 1; FIG. 7 is a right view of the deployment tool shown in FIG. 1; FIG. 8 is a exploded perspective view of the FIG. 1 deployment tool showing the relationship between various parts of the tool; and,

FIG. 9 is a perspective view showing the FIG. 1 tool inserted into an incision of a patient.

The broken line structure in FIG. 8 depicts an encapsulation device and the broken line structure in FIG. 9 depicts an incision; wherein the broken lines show environment and form no part of the claimed design. The dash dot lines in FIG. 8 show the exploded view and forms no part of the claimed design.
